UNITED STATES PATENT OFFICE

93,928

DESIGN FOR A COCKTAIL SHAKER

Ralph N. Kircher, West Bend, Wis., assignor to West Bend Aluminum Company, West Bend,
Wis., a corporation of Wisconsin

Application September 24, 1934, Serial No. 53,387

Term of patent 7 years

To whom it may concern:

Be it known, that I, RALPH N. KIRCHER, a citizen of the United States residing at West Bend, Wisconsin, in the county of Washington, have invented a new, original, and ornamental Design for Cocktail Shakers of which the following is a specification, reference being had to the accompanying drawing forming a part of this specification, and in which:

The single figure is a perspective view of a cocktail shaker showing my new design.

I claim:

The ornamental design for a cocktail shaker as shown.

RALPH N. KIRCHER.
